UNITED STATES PATENT OFFICE.

SAMUEL T. MULFORD, OF PHILADELPHIA, PENNSYLVANIA.

SAFETY-CLIP DEVICE FOR WINDOWS.

1,359,093.

Specification of Letters Patent. Patented Nov. 16, 1920.

Application filed January 19, 1920. Serial No. 352,348.

To all whom t may concern:

Be it known that I, SAMUEL T. MULFORD, a citizen of the United States, residing at Philadelphia, in the county of Philadelphia and State of Pennsylvania, have made a certain new and useful Invention in Safety-Clip Devices for Windows, of which the following is a specification.

This invention relates to safety devices to prevent the raising of a window sash.

The object of the invention is to provide a safety device of the nature referred to which is simple in construction, capable of being easily and quickly applied for use, economical to manufacture, and efficient in operation.

The invention consists substantially in the construction, combination, location and relative arrangement of parts, all as will be more fully hereinafter set forth, as shown in the accompanying drawing and finally pointed out in the appended claims.

Referring to the accompanying drawing, Figure 1 is a view in perspective, parts broken off, and parts broken out, showing a safety clip device embodying my invention applied to prevent the lower sash of a window from being raised in the window frame.

Fig. 2 is a similar view showing the application of my invention to the two sashes of a window to prevent the lower one from being raised or the upper one from being lowered.

Fig. 3 is a view in perspective of a safety device or clip embodying my invention.

Fig. 4 is a view similar to Fig. 1 showing a slightly modified arrangement embodying the principles of my invention.

Referring to the drawing, reference numeral 5 designates a window frame which may be of the usual or ordinary construction adapted to receive the upper and lower window sashes 6, 7, in the usual manner and in which said sashes may be raised and lowered and 8 designates the usual sash cord for the lower sash.

Experience has shown that unauthorized entry into houses, buildings, or the like, by burglars and others is frequently effected by jimmying the windows, that is, by either tampering with the ordinary sash locks usually applied to fasten windows or by

forcing the same loose by inserting a jimmy or bar underneath the bottom of the lower sash and forcing such sash upwardly in its guides in the window frame. The sash locks ordinarily supplied to window sashes are not usually constructed in such a manner as to be capable of resisting the force or pressure applied in jimmying the sash, and some times they are of such construction as to permit the easy insertion of suitable tools between the two sashes of the window for cutting or otherwise releasing these fastening devices.

It is among the special purposes of my present invention to provide a safety clip device of simple construction and which is economical to manufacture, for insertion between the edge of the lower sash and the adjacent surface of the frame in which the sash is mounted to slide, or between the abutting faces of the two sashes of the window, the clip being so constructed as to bite into the surface of the window frame in the one case or into the surface of the adjacent window sash in the other case, or to otherwise form an engagement, such as to prevent the form of a jimmy from effecting the raising of the lower sash or, in the other instance referred to, the lowering of the upper sash. In Fig. 3 I have shown a form of safety clip device embodying my invention. This form is made of a sheet metal stamping 9 which is slit longitudinally part way of its length in two parallel lines, as indicated at 10, 11, thus forming three tongues 12, 13 and 14. The outer tongues 12, 14, are then bent over laterally with respect to the plane of the stamping 9 in one direction, while the intermediate tongue 13 is bent or deflected slightly in the other direction and the free edge of said tongue 13 is preferably beveled off or sharpened, as indicated at 15.

In the use of a safety clip such as above described, the body of the stamping 9 is inserted, for example, between the edge of the lower sash 7, and the wall of the groove or guideway in the window frame 5, in which said sash slides, with the tongues 12, 14, bent over upon the window sash and the tongue 13 bent over toward the adjacent wall surface of the window frame with the sharpened edge 15 thereof in engaging con-

tact with such surface. By reason of the engagement of the tongues 12, 14, over the upper edge of the sash, any attempt to raise said sash in its guideways will cause the 5 sharpened edge 15 of tongue 13 to bite into the surface of the channel or guideway in the casing and hence prevent said sash from being raised. The greater the power applied to the lower sash to raise it, the 10 deeper and greater will the sharpened edge 15 of the tongue 13 bite into the casing, thereby efficiently resisting the raising of the sash.

Instead of the safety clip, constructed as 15 above described, being inserted between the edge of the sash and the adjacent surface of the casing, it may be inserted between the two sashes of the window as shown in Fig. 2.

In this case the bent-over tongues 12, 20 14, engage over the upper surface or member of the lower sash, while the beveled tongue 13 presents toward and its sharpened edge 15 engages with the adjacent surface of the upper sash 6. In this case any attempt either to raise the lower sash or to 25 lower the upper sash will cause the sharpened edge 15 to bite into the surface of the upper sash and hence resist such movements of the sashes.

Should it be desired to avoid the mar-ring effect of the sharpened edge 15 biting into the surface of the casing or of the upper sash, the advantages of my invention 30 may be attained by applying a rack 16 to the surface to be engaged by the intermediate tongue of the clip device as shown in Fig. 4.

It may also be desirable to provide means 40 by which the engagement of the intermediate tongue with the adjacent surface of the window casing or the upper sash, as in Figs. 1 and 2, or with the rack 16, as in Fig. 4, may be detached, as for example, when it is 45 desired to remove the safety device to permit the sashes to be operated in the ordinary manner. To accomplish this result in accordance with my invention a central tongue may be made of somewhat extended length 50 as indicated at 17, Fig. 4, whereby its natural flexibility or resiliency will permit the engaging edge surface or end thereof to be withdrawn from engaging relation. To facilitate the necessary slight upward bending 55 of the tongue 17 to secure this result, a lip 18 may be stamped out of the tongue 17 to afford means to be grasped by the hand or thumb, and by which the tongue may be deflected outwardly sufficiently to disengage 60 its biting edge and permit the clip to be removed.

Having now set forth the objects and nature of my invention and a construction embodying the principles thereof, and having explained its application in various rela-

tions, what I claim as new and useful and 65 of my own invention, and desire to secure by Letters Patent is:—

1. A safety clip device consisting of a sheet metal stamping, slotted longitudinally for a portion of its length, from one end 70 thereof, to form integral tongues, said tongues being bent or deflected in opposite directions from the plane of the body of the stamping.

2. A safety clip device consisting of a 75 sheet metal stamping, slotted longitudinally for a portion of its length, from one end thereof, to form integral tongues, said tongues being bent or deflected in opposite directions from the plane of the body of 80 the stamping, the free end of one of said tongues being sharpened.

3. A safety clip device for window sashes consisting of a sheet metal stamping having 85 longitudinal slits extending part way the length thereof from one end and in parallel lines to form integral tongues, the outermost tongues being bent or deflected in one direction and the intermediate tongue being 90 bent or deflected in the opposite direction from the plane of the body of the stamping.

4. A safety clip device for window sashes consisting of a sheet metal stamping having 95 longitudinal slits extending part way the length thereof from one end and in parallel lines to form integral tongues, the outermost tongues being bent or deflected in one direction and the intermediate tongue being 100 bent or deflected in the opposite direction from the plane of the body of the stamping, the free edge of said intermediate tongue being sharpened.

5. A safety clip device for window sashes consisting of a sheet metal stamping having 105 longitudinal slits extending part way the length thereof from one end and in parallel lines to form integral tongues, the outermost tongues being bent or deflected in one direction and the intermediate tongue being 110 bent or deflected in the opposite direction from the plane of the body of the stamping, the free edge of said intermediate tongue being sharpened, in combination with a rack 115 with which the free end of one of said tongues engages.

6. A safety clip device for window sashes consisting of a sheet metal stamping having 120 longitudinal slits extending part way the length thereof from one end and in parallel lines to form integral tongues, the outermost tongues being bent or deflected in one direction and the intermediate tongue being 125 bent or deflected in the opposite direction from the plane of the body of the stamping, the free edge of said intermediate tongue being sharpened, in combination with a rack with which the free end of one of

said tongues engages, and means connected with said engaging tongue to deflect the same to release its engagement with the rack.

5 7. In a safety clip device for window sashes, a sheet metal stamping formed with integral tongues at one end, said tongues

being bent or deflected in opposite directions from the plane of the body of the stamping, one of said tongues having a lip. 10

In testimony whereof I have hereunto set my hand on this 12th day of January A. D., 1920.

SAMUEL T. MULFORD.
